UNITED STATES PATENT OFFICE.

HENRY REINCKE, OF DES PLAINES, ILLINOIS.

HENHOUSE-DOOR.

1,381,015.

Specification of Letters Patent. Patented June 7, 1921.

Application filed March 22, 1921. Serial No. 454,456.

To all whom it may concern:

Be it known that I, HENRY REINCKE, a citizen of the United States, residing at Des Plaines, in the county of Cook and State 5 of Illinois, have invented certain new and useful Improvements in Henhouse-Doors, of which the following is a specification.

The invention relates to hen house doors and exits, and has for its object to provide 10 a device of this character, which may be closed from the outside for preventing entrance of animals, such as prey upon fowl, and so constructed that when a chicken desires to leave the hen house, the weight of 15 the chicken on a depressible member will release a spring latch and allow the hen house door to swing open upon its hinges under the influence of a spring.

A further object is to provide means 20 whereby the spring opened door may be permanently held against opening under the impulse of the operating spring, thereby preventing exit of the fowl from a hen house.

A further object is to provide a hen house 25 exit comprising a casing having a passage therethrough to one side of said casing and at one end thereof a vertically hinged door is provided, said door being provided with spring means for opening the same. Also to 30 provide a pivoted latch bar within the passage and pivoted to the side thereof, said latch bar being normally held downwardly by a spring, and its hooked end in engagement with a keeper carried by the free end 35 of the door, said latch bar holding the door closed and to provide a pivoted tread member having a connecting bar connection with the rear end of the latch bar and on said tread member, the fowl leaving the hen 40 house will step thereby depressing the tread member and releasing the door, allowing the same to be opened by its operating spring.

With the above and other objects in view the invention resides in the combination and 45 arrangement of parts as hereinafter set forth, shown in the drawings, described and claimed, it being understood that changes in the precise embodiment of the invention may be made within the scope of what is 50 claimed without departing from the spirit of the invention.

In the drawings:—

Figure 1 is a side elevation of the hen house exit.

Fig. 2 is a vertical sectional view through 55 the exit.

Fig. 3 is a horizontal sectional view taken on line 3—3 of Fig. 1.

Fig. 4 is a rear view of the exit.

Fig. 5 is a detail view of the hooking 60 means for holding the door shut and against operation.

Referring to the drawings, the numeral 1 designates a rectangular shaped casing which may be disposed in a hen house opening and 2 an exit passage through said casing through which poultry passes in entering and leaving the hen house. Pivoted as 65 at 3 to one of the sides 4 of the casing 1 is a lever 5, the forward end of which terminates in a hooked member 6 adjacent the inner face of the door 7 which is hinged as 70 at 8 to one of the sides 4. Hooked member 6 engages over a lug 8 carried by the door 7 adjacent its free end and holds said door 75 in closed position as shown in Fig. 3, against the action of the leaf spring 9, one end of which spring is secured at 10 to one of the side members 4 of the casing 1 and the other end disposed in engagement with the inner 80 face of the door 7, said leaf spring forming means for forcing the door 7 to open position when the hooked end 6 of the lever 5 is raised out of engagement with a lug 8 carried by the door and against the action 85 of the leaf spring 11. Leaf spring 11 normally holds the hooked end 6 of the lever 5 in down position as shown in Fig. 2, so that the door will be held closed to exclude 90 entrance of animals which destroy fowl. After the fowl has entered the hen roost or house the operator closes the door 7 for the night for excluding animals from the hen house. However in the morning when the fowls start from the hen house, one of them 95 will step on the hinged tread member 12 and the weight of the fowl will force said tread member downwardly to the dotted line position shown in Fig. 2. When the tread member 12 is forced downwardly a downward 100 pull is imparted on the bar 13 which is pivoted as at 14 to the tread member and at 15 to the rearwardly extending arm 16 of the pivoted lever 5, which action will rock the pivoted lever on its pivotal point 3 and 105 raise the hook 6 of said lever out of engagement with the lug 8 against the action of the spring 11 and release the door 7, thereby 110 allowing the door to be forced to open position by the leaf spring 9.

The arm 16 of the pivoted lever 5 extends through a U-shaped cleat 17, which cleat

limits the upward and downward movement of the arm 16 and consequently limits the upward and downward movement of the hook 6. The end of the hook 6 is beveled as at 18 so that when the door is closed manually by the operator, the lug 8 will engage the bevel end 18 and force said hooked end upwardly until the lug is received in the notch 17 of the lever and held therein by the action 10 of the leaf spring 11 until a fowl releases the same when it desires to leave the hen house and moves through the passage 2 in the direction of the arrow *a*.

If it is desired to lock the door 7 so that 15 the fowl cannot leave the hen house at all, the pivoted hook 20 is moved into engagement with the headed lug 21 carried by the free edge of the door 7, this being desirable under weather conditions, when it is essential to maintain fowl housed.

The invention having been set forth what is claimed as new and useful is:—

A fowl operated closure for hen house openings, said closure being hinged to the 25 hen house and positioned to register with the opening therein when closed, a leaf spring engaging said closure and forming means for forcing the same outwardly when

released, a lever pivoted adjacent the closure and inwardly thereof, one end of said lever 30 being provided with a hook, a lug carried by the door and adapted to be engaged by said hook for holding the closure in closed position, a leaf spring engaging the hook carrying end of the lever for normally holding the same in engagement with the hook, means for limiting the pivoted movement of the pivotal lever, a bar pivotally connected to said lever, a substantially horizontally disposed hinged tread member disposed inwardly of the closure, said bar being pivotally connected to said tread member and forming means whereby as the tread member 35 is forced downwardly by the weight of the fowl the pivoted member will be rocked 40 against the action of its spring and the closure released, thereby allowing the closure to be forced to open position by the action of its spring.

In testimony whereof I have signed my 50 name to this specification in the presence of two subscribing witnesses.

HENRY REINCKE.
